UNITED STATES PATENT OFFICE

2,185,028

GRATE

Albert Hoiland, Fargo, N. Dak.

Application October 29, 1937, Serial No. 171,738

1 Claim. (Cl. 126—163)

My invention relates to an improvement in grates, wherein it is desired to provide a fuel supporting device by the use of which inexpensive fuel such as lignite may be readily burned.

5 In some parts of the country large deposits of lignite coal and other cheap fuels of this nature are found. These fuels are used to some considerable extent, but the use has been somewhat restricted due to the fact that the fuel is difficult 10 to burn. Lignite coal, for example, usually contains a large percentage of moisture and must be dried considerably before burning. Considerable air is required in the burning of this fuel, and it has been found that the fuel has a tendency to 15 pack tightly together preventing the passage of air therethrough.

It is the purpose of the present invention to provide a grate which is suitable for use in the burning of fuel of this sort. This grate provides 20 a means of introducing air into the fuel and also provides a manner in which the fuel may be pre-heated and accordingly dried. The dried fuel of course will burn very readily when sufficient air is introduced.

25 It is a purpose of the present invention to provide a means of introducing air into the fuel in a substantially horizontal direction so that the flames are naturally directed toward the sides of the fire pot, creating a greater heating effect than 30 would otherwise be possible. The amount of air introduced varies with the depth of fuel, so that the fuel at the bottom of the bed of fuel will receive a greater amount of air than the fuel near the top of the fuel bed.

35 It is a purpose of the present invention to provide a device which is mounted in the center of the fire pot so that the fuel to be burned will be positioned between this central device and the side walls of the fire pot. The walls of the furnace will accordingly be thoroughly heated by the 40 fire in intimate contact therewith, and the depth of the fuel bed along the wall thereof is considerably increased for the amount of fuel used.

It is an added feature of my invention to provide 45 a grate which may be rested directly upon the usual grates normally found in the ordinary furnace. Accordingly, my grate may be added to the usual furnace without necessity of reconstructing the furnace or of changing the grates. 50 In installing my grate, it is only necessary to provide an open space on the grates in the center of the fire pot, and to insert my grate to rest upon the usual furnace grates substantially at the center of the fire pot.

55 It is an added feature of my invention to pro-

vide a grate which may be formed in sections and built to any desired length to fit a boiler or fire pot of any size. Accordingly, for commercial boilers and the like having large fire pots, the size of the grate may be readily increased without the necessity of building a grate of proper size to fit each separate boiler.

These and other objects and novel features of my invention will be more clearly and fully set forth in the following specification and claim.

10 In the drawing forming a part of my specification:

Figure 1 is a perspective view of my grate in usual form for use in a small fire pot.

Figure 2 is a central cross-sectional view 15 through the grate illustrated in Figure 1, showing the same in place upon the grates of a furnace.

Figure 3 is an exploded view of a sectional grate, the sections of which have been separated.

The grate A is illustrated as having a top plate 20 10 and a series of co-axial rings or bands 11 and 12. The ring 11 is of slightly larger diameter than the top plate 10 and is spaced therefrom. The lower band 12 is of larger diameter than the ring or band 11 and is spaced from this ring 11. 25 The space between the rings or bands 11 and 12 is greater than the space between the upper band 11 and the top plate 10. Obviously, the device may be formed with three or more bands such as 11 and 12, each increasing in thickness. As the 30 rings or bands increase in thickness, the space between the bands also increases, as it is desired to vary the opening between the bands in proportion to the depth of these bands.

It has been found that the deeper the bed of 35 fuel, the more air is required to burn this fuel. Accordingly, the space between superimposed bands is greater near the bottom of the grate than at the top of the same. The top 10 and the bands 11 and 12 are held in proper spaced relationship by connecting ribs 13 which are angularly disposed in spaced relationship within the bands 11 and 12, as illustrated in Figures 1 and 2 of the drawing. These ribs 13 extend from the lowest ring 12 to the top plate 10 and extend beneath the top plate at 14 to reinforce the same.

The grate A in use is designed to rest upon the usual grate of a furnace or burner, these grates being diagrammatically indicated at 15 in Figure 2 of the drawing. While the grates are not 50 usually of the type disclosed in Figure 2, in view of the large number of forms which might be used, these grates are illustrated as being square or rectangular in cross-section.

The side walls 16 of the fire pot 17 of the fur-

nace taper inwardly at the bottom in usual formation, and the fuel when introduced into the furnace drops between the grate A and the side walls 16. Of course, in building a fire, 5 kindling of some sort is usually used, and the fuel is heated to the ignition point, and accordingly, when the fire is well under way, the fuel usually surrounds the side walls of the grate and completely covers the same. The top forms a 10 supporting shelf for heating fuel introduced into the fire, and the portion of the fuel above this top 10 cokes thoroughly while drying and burns readily when broken up. It is therefore advisable to introduce new fuel onto the top of the grate A 15 so that the portion of the device may act as a coking oven to prepare the fuel for burning. Before placing fuel into the fire, it may become customary to break up the coke formed above the top 10 and to spread this preheated fuel about 20 the sides of the grate A. The new fuel may then be introduced again onto the top of the grate. In order to provide a grate suitable for fitting any boiler without providing separate patterns for each size of grate, I provide a grate formed 25 with each sections 19 as illustrated in Figure 3 of the drawing and central sections 20, as also illustrated in this figure. The end sections 19 are identical and are formed similarly to a half of the grate illustrated in Figures 1 and 2. In other 30 words, the end sections 19 would be formed similarly to the construction resulting from cutting centrally through the circular grate A, the cut extending through the reinforcing ribs 13. The end sections 19 are provided with a semi-circular 35 top 21 and a band 22 of larger diameter than the top 21 and spaced somewhat below the same. A third band or semi-circular ring 23 is spaced a greater distance from the band 22 than this band 22 is spaced from the top 21. Reinforcing 40 ribs 24 connect the bands 22 and 23 with the top 21 to hold these parts in desired spaced relationship. Openings 25 are provided in the reinforcing ribs 24 to accommodate bolts 26 by means of which the sections 19 and 20 can be connected. 45 The central sections 20 are formed with a top 27 and with side bars 29 and 30 which are spaced similarly to the bands 22 and 23. Reinforcing ribs 31 are formed at the ends of the sections 20

for spacing the bars 29 and 30 from the top 20 and for holding the parts in desired relationship. A central reinforcing bar member 32 may also be provided if it is desired to provide additional strength. The contour of the ends of the central 5 section 20 is identical with the contour of the flat end of the end sections 19 and these sections fit intimately together, being secured in abutting relationship by the bolts 26. Openings 33 are formed in the reinforcing ribs 31 to accommodate 10 the bolts 26 passing through the reinforcing ribs 24 of the end sections 19.

It is obvious that under the teachings of this construction, a grate may be formed with a series 15 of central sections 20 interposed between the end sections 19 to provide a grate of any desired length. It is also believed obvious that any number of bands or rings such as 11 and 12 may be formed so that the substantially frustro-conical 20 grate may be formed of three and more rings 20 rather than two as illustrated. The operation of such a construction would be identical with that previously described.

In accordance with the patent statutes I have 25 described the principles of construction of my grate, and while I have endeavored to set forth the best embodiment thereof, I desire to have it understood that this is only illustrative of a means of carrying out my invention, and that 30 obvious changes may be made within the scope 30 of the following claim without departing from the spirit of my invention.

I claim:

A sectional grate comprising a pair of substantially semi-circular substantially flat top 35 sections, a pair of semi-circular bands below the level of said top sections and arranged one above the level of the other, ribs connecting said bands and said top sections to hold said bands and top sections in proper relationship, and a center section 40 interposed between said semi-circular sections, said center section including a substantially flat top member extending between said semi-circular flat top sections, and side bands 45 abutting said bands on said semi-circular sections, and means securing said center section to said semi-circular sections.

ALBERT HOILAND.
